US00D887789S

(12) **United States Design Patent** (10) **Patent No.:** **US D887,789 S**
(45) **Date of Patent:** **** Jun. 23, 2020**

(54) **CONTAINER**

(71) Applicant: **YETI Coolers, LLC**, Austin, TX (US)

(72) Inventors: **Roy Joseph Seiders**, Austin, TX (US);
James William Sonntag, Austin, TX (US);
Christopher Mall Keller, Austin, TX (US);
Steve Charles Nichols, Austin, TX (US)

(73) Assignee: **YETI Coolers, LLC**, Austin, TX (US)

(**) Term: **15 Years**

(21) Appl. No.: **29/673,008**

(22) Filed: **Dec. 11, 2018**

Primary Examiner — Terry A Wallace

(74) *Attorney, Agent, or Firm* — Banner & Witcoff, Ltd.

(57) **CLAIM**

The ornamental design for a container, as shown and described.

DESCRIPTION

FIG. 1 is a top, front, right perspective view of a container showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the remainder of the container show features that form no part of the claimed design.

1 Claim, 7 Drawing Sheets

See application file for complete search history.
